UNITED STATES PATENT OFFICE.

LANK HUGHES, OF WASHINGTON, DISTRICT OF COLUMBIA.

TOOL-HOLDING DEVICE.

Application filed June 10, 1926. Serial No. 115,135.

This invention relates to containers for holding tools and protecting them against the corroding effect of the atmosphere, and more especially it relates to that form of container adapted to hold paint brushes in such manner as to prevent them from becoming dry and hard and unfit for future use. The particular object of this invention is to provide that form of a container 10 of the general type described in my application filed May 17, 1924, Serial Number 714,054, with a particular type of tool holding and gripping means that may be easily operated and is adapted to receive and hold 15 the tools securely and permit the release thereof by the operation of spring controlled clamps which engage and hold the tools. The container described herein is made of sheet metal; but any other metal or material adapted for such use may be used. 20 It is a purpose of this device in connection with the particular form of tool holding means to provide a container that will support the tools in an air-tight condition and 25 preserve them against the corroding influence of the atmosphere. This is done by secluding the air from the free contact with the tools and by providing a volatile substance that tends to moisten and preserve 30 the tools in a pliable condition.

These and other advantages will appear in the following description, taken in connection with the drawings, which exemplify one embodiment of this device and in which: 35 Figure 1 is a side view of a container showing the closure applied thereto,

Figure 2 is a vertical cross section of the container and the closure as a whole, showing the special form of tool holding 40 device,

Figure 3 is a top plan view of the metallic tool holding ring and the special form of gripping means thereon,

Figure 4 is a fragmentary view of the tool holding ring and showing a bottom plan 45 view of said fragment,

Figure 5 is a fragmentary view of the tool holding ring showing the gripping jaws and the finger means by which the said jaws 50 are operated,

Figure 6 is a section of the tool holding ring showing the particular means by which an operating spring is supported and the particular means by which the ring is supported in the container.

The invention described herein is an im-

provement on the invention described in my prior application mentioned above. The numeral 1 represents the body of the container which on the drawing is shown to be cylindrical in form, and has a base member indicated by the numeral 2. Located in the center of the container and upon member 2, is a vessel, 3, adapted to contain or hold some volatile liquid, such as turpentine or a like substance. Near the upper part of the container there is a series of studs projecting within the container and forming supports for a tool holding ring which is to be described later. These studs, 4, not only form means for supporting the tool holding ring, but they also form part of the means by which a closure, 7, may be securely engaged with the container. The closure is of the same general shape as that of the container and is adapted to fit within the container and to engage the studs for holding the container and closure in air-tight relation to each other. For the purpose of providing a more nearly air-tight closure the upper part of the container is provided with a rib, 8, and the closure is provided with a similar rib, 9, which forms a shoulder engaging the upper part of the container when the closure is placed in closed position. The upper part of the closure is indicated by the numeral 10, and has attached thereto a handle member, 11, by which the closure may be operated in placing it on or taking it off the container, or by which the device as a whole may be carried from place to place.

Located in the upper part of the container and supported by the studs, 4, is a tool holding ring, 5, made of sheet metal and supporting and carrying the particular form of tool gripping means which is the chief feature of this application. The tool holding ring, 5, is circular in form and supports a series of concentrically arranged tool gripping jaws. In the present device there are shown two series of these concentrically arranged gripping means. In each series there are two or more individual gripping means. In the present instance, three such means are shown in each series. Each gripping means is composed of a fixed jaw and a movable jaw. The fixed jaw is integral with the body of the ring and has formed therein a seat for the reception of the tools. This seat in the outer series is indicated by the numeral 12. The movable, or pivotal, jaw, 13,

is mounted by a pivot means, 14, upon the ring, 5, and is provided with a seat, 15, cooperating with the seat, 12, for engaging the tools. That part of the pivotal jaw, 13, 5 remote from the gripping seat, 15, is provided with two stop members, 16 and 17, and a spring engaging lip member, 18. The lip member, 18, is at all times in engagement with the spring, 19, which, through its action 10 upon the lip member, 18, tends to keep the jaws open or closed owing to its relative position in regard to the pivot, 14. The spring, 19, is supported by suitable lugs, 20, and extends around the outer circumference of the 15 tool supporting ring. This spring, 19, may be in one piece or more. In the present instance it is shown to be in three sections. The spring, 19, is always in engagement with the lip member, 18, and thereby serves at all 20 times to hold the jaws open or closed. The stop member, 16, engages the spring, 19, when the pivotal jaw is open, and prevents the lip, 18, from passing off what might be called "dead center". The stop, 17, engages 25 the spring, 19, when the jaws are closed. When the pivotal jaw is open, the inner shoulder or heel of the seat projects slightly over or out beyond the tool seat provided by the fixed jaw, as is shown by the numeral 21. 30 This being the case, when the pivotal jaw is open and a brush or any other tool is placed within the jaw and brought in contact with the heel, 21, the pressure on the heel causes the lip, 18, to move away from dead center, 35 and the spring acting upon the lip, 18, will force the jaws together and secure the tools. For the purpose of convenience and facility in operating the pivotal jaw, 13, a finger piece, 22, is provided. The foregoing is a 40 description of one of the gripping means of the outer series of said means. The inner series is constructed of gripping means of substantially the same nature. Each gripping means is composed of a fixed jaw, 23, 45 projecting from the body of the ring, and a pivotal jaw, 24, pivotally supported in connection with the fixed jaw by a pivot, 25. These jaws in cooperation with each other, 50 form a tool seat, 26, more or less circular in shape. The end of the pivotal jaw remote from the tool seat, 26, is provided with two spring engaging lips, 27 and 28. The lip, 28, serves the same purpose that the lip, 18, 55 serves in the outer series, while the lip, 27, acts as a stop to prevent the jaws from becoming too widely opened and to stop the lip, 28, at such a time that it forms with the pivot and the center of the tool seat a straight line when the jaws are open. When 60 the pivotal jaw is open, the inner part of the tool seat thereof projects beyond the corresponding part of the fixed jaw, as is shown by numeral 29, and forms an abutment against which the tool strikes when it is 65 placed in engagement with the tool seat, and

thereby throws the lip, 28, out of alignment with the pivot, 25, and the seat, 26, and through the spring, 19, tends to snap the jaws together. For purpose of facility and ease in operating the jaws to close them or 70 open them, each jaw is provided with a finger piece, 30. The spring that engages the lips, 27 and 28, is the same spring that engages and operates lip 18.

For the purpose of supporting the tool ring within the container, there is formed on the ring two or more stirrup members, 31, which are adapted to engage the stud members, 4. These stirrup members may be integral with the the ring or may be of separate material attached thereto by any suitable means. The stirrup members, 31, and the stud members, 4, cooperate with each other in supporting the ring and in holding the ring in spaced relation to the container, so that when the closure is placed in engagement with the container, it will fit within the container and between the walls thereof and the ring. For the purpose of engaging the studs, 4, the closure is provided with a series of bayonet slots, 6, into which the studs, 4, fit and engage when the closure is applied with the container. These bayonet slots are so constructed that the closure may be placed upon the container by adjusting it therewith so that each slot will receive a stud, and when the container is rotated slightly the stud will engage another part of the slot to hold the closure in engagement with the container. For the purpose of preventing the closure from becoming detached, there is provided a locking means indicated by the numeral 32. There is also provided foot piece, 33, to be used by the foot when the closure is being applied to the container. 100

Having described my invention, what I claim as new and wish to protect by Letters Patent is:

1. In a tool holding device, a container, a plurality of tool holding means within the container, each of said tool holding means consisting of a fixed part and a relatively movable part, a common spring means acting upon the movable parts and adapted to hold said movable parts in either open or closed position in regard to the fixed parts. 110

2. In a tool holding device, a container, a ring within the container adapted to carry a plurality of tool holding means, each of said tool holding means consisting of a fixed part and a relatively movable part, a common spring means supported by the ring and engaging the movable parts and adapted to hold said movable parts in either open or closed position. 120

3. In a tool holding device, a container, a tool holding ring within the container and held in spaced relation thereto, a plurality of fixed clamp members associated with the ring, a plurality of movable clamp mem- 130

bers associated with the fixed clamp members, and a common spring means engaging the movable clamp members adapted to hold them in or out of engagement with the fixed 5 clamp members.

4. In a tool holding device, a container, a tool holding ring within the container, a plurality of fixed clamp elements extending from the ring, a plurality of movable clamp 10 elements pivotally connected with the ring and cooperating with the fixed clamp elements, and a spring means supported by said ring and extending around interior of the closed container and adapted to hold the 15 movable clamp elements in relation to the fixed clamp elements.

5. In a tool holding device, a container, a tool holding ring within the container, a fixed clamping element integral with the 20 ring, a movable clamping element pivotally connected with the ring, a spring supported by the ring and engaging the movable clamping element to hold it in open or closed position in relation to the fixed clamping 25 element, and a heel means adapted to be engaged by the tool when it is placed within the clamping element to move the movable

clamping element and cause the spring to snap the clamping element engaging with the tool.

30

6. In a tool holding device, a fixed clamping element supported thereby, a movable clamping element held in pivotal relation to the fixed clamping element, means for holding the movable clamping element in or out of engagement with the fixed clamping element, and means associated with the movable clamping element to be engaged by the tool to snap the clamping elements in engagement with the tool.

40

7. In a tool holding device, a fixed clamping element supported thereby, a movable clamping element held in pivotal relation to the fixed clamping element, spring means attached to the fixed clamping element, 45 means on the movable clamping element cooperating with the spring means to hold the movable clamping element either open or closed, and means on the movable clamping element to limit the movement of the movable clamping element as it swings open or closed due to the action of the spring means.

50

In testimony whereof I affix my signature.
LANK HUGHES.
